DESCRIPTION

FIG. 1 is a perspective view of a keyhole saw handle showing my new design;

FIG. 2 is a top plan view thereof;

FIG. 3 is a bottom view thereof;

FIG. 4 is a front elevational view thereof;

FIG. 5 is a side elevational view thereof with a saw blade and tensioning means shown in phantom line;

FIG. 6 is an elevational view of the opposite side; and,
FIG. 7 is a rear elevational view.

The broken line showing in FIG. 5 is for illustrative purposes only and forms no part of the claimed design.

FIG. 1

FIG. 2

FIG. 3

FIG. 4
